UNITED STATES PATENT OFFICE.

ERNEST C. BEAUMONT, OF BOSTON, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

1,393,486.

Specification of Letters Patent.

Patented Oct. 11, 1921.

Application filed November 21, 1918. Serial No. 263,536.

To all whom it may concern:

Be it known that I, ERNEST C. BEAUMONT, a citizen of the United States, residing at Boston, in the county of Suffolk and State 5 of Massachusetts, have invented certain Improvements in Methods of Making Shoes, of which the following description, in connection with the accompanying drawings, is a specification, like reference characters on the drawings indicating like parts in the several 10 figures.

This invention relates to methods of making shoes and is herein described and illustrated with reference to its application to 15 the manufacture of stitchdown shoes.

Many of the difficulties attendant upon the manufacture of shoes of this type have been overcome by the use of the method disclosed and claimed in United States Letters 20 Patent No. 1,117,086, granted November 10, 1914, upon the application of Adam H. Prenzel. This method is very rapid and effective for working into lasted position and securing the upper at the toe and heel ends 25 of the shoe without previously molding the upper, but when this method is used at the sides of the shoe, the staples driven in the angle between the side of the last and the projecting margin of the sole to secure the 30 upper in place, are frequently visible inside the shoe when the shoe is critically examined. This is particularly noticeable when the shoe has a deeply undercut shank, as in women's shoes, and the staples, therefore, have to be driven at a smaller angle to the plane of 35 the sole. Furthermore, by bending the upper at the side of the shoe down against the inner face of the sole, the staples may be exposed on the outside of the shoe also and 40 some customers object to shoes in which the fact that staples have been employed in their manufacture can be detected. At the toe and heel the toe and heel stiffeners render it impossible so to bend an upper as to expose 45 the staples at the outside of the shoe or inside of the shoe at the heel, and at the toe, of course, the staples are invisible on the inside of the shoe.

An object of this invention is to provide 50 a method which, while retaining the advantages of prior methods, will avoid the

disadvantages attendant upon the practice of these methods and will be thoroughly effective and satisfactory.

With these objects in view, my improved 55 method consists in preparing a last with a sole attached thereto with its margin projecting beyond the bottom of the last; assembling the upper upon the last; then lasting an end or the ends of the upper by 60 forcing various portions of the upper into the angle between the side of the last and the projecting margin of the sole and securing them by staples driven in said angle. Usually it is desirable also to insert a staple 65 at each side of the shoe opposite the ball of the shoe and, of course, if it is desired the heel portion of the upper may be turned in and lasted to the heel seat in the usual manner. Next the last is removed from the 70 shoe and the upper at the sides of the shoe is secured to the margin of the sole by the use of stitches, any suitable sewing machine being employed for the purpose, for example, a straight needle machine, the seam 75 preferably extending from the lasted portion at the toe to the lasted portion at the heel seat on each side of the shoe. The last is now replaced in the shoe and the shoe completed by the attachment of an outsole 80 and welt in the usual manner.

In the drawing,—

Figure 1 shows an unmolded upper and an innersole assembled on a last;

Fig. 2 shows the shoe after the upper has 85 been lasted and secured to the innersole at the toe and heel ends;

Fig. 3 is a detailed view of mechanism which may be employed in performing the staple lasting step of this method; 90

Fig. 4 shows the shoe after the last has been removed and the upper has been sewn to the innersole at the sides;

Fig. 5 is a detail illustrating sewing mechanism which may be employed in performing the sewing step of this method; and 95

Fig. 6 is a view of the shoe after it has been completed.

In the practice of my improved method, an innersole A is secured to the bottom of a 100 last B and an unmolded upper C is assembled upon the last, the condition of the work at

this stage being clearly indicated in Fig. 1. The upper at the toe end, and preferably also at the heel end, is next drawn over the last in intimate contact therewith, worked 5 into the angle between the side of the last and the projecting margin of the sole and secured to the innersole substantially in said angle by staples D having their bars extending in the direction of the edge of the last. 10 The line of staples at the toe end of the shoe may extend from the tip seam E on one side about the toe to the tip seam on the other side and preferably a single staple F is driven at the ball of the shoe on each side of 15 the shoe. The line of staples at the rear end of the shoe may extend from a point G adjacent to the heel breast line on one side of the shoe about the heel to the heel breast line on the other side of the shoe. A very effective 20 machine for performing this lasting and stapling operation is disclosed and claimed in United States Letters Patent No. 1,117,087, granted November 10, 1914, upon an application of Adam H. Prenzel, and United States Letters Patent No. 1,291,754, granted 25 Jan. 21, 1919, upon an application of Matthias Brock, although, of course, the lasting and stapling operations may be effected in other ways and by other apparatus without departing from this invention.

Mechanism suitable for performing the lasting and stapling step of this method is shown in Fig. 3 and includes a rest R having a staple clenching face P and a tool T which 30 is also the nozzle of the stapling mechanism. Relative movement is effected between the rest R and the tool T to cause the tool to last the upper against the side of the last and force it into the angle between the side of 35 the last and the projecting margin of the sole where it is secured, substantially in said angle, by a staple driven through the tool T and clenched upon the face P of the rest R.

At this stage in the manufacture of the 40 shoe, it is generally desirable to remove the last in order that the sewing of the upper to the innersole at the sides of the shoe may be more conveniently and effectively performed and this is particularly desirable when the 45 shank of the last is deeply undercut on the inner side, as is frequently the case particularly in women's shoes. The last having been removed, the upper is secured by a line of stitches H to the innersole along the side 50 of the shoe from the point G secured by a staple adjacent to the breast line to the point E secured by a staple adjacent to the tip line, the stitches, therefore, traversing the point F at the ball of the shoe which may 55 also have been secured by a staple. The sewing operation is repeated upon the opposite side of the shoe. It is understood, of course, 60 that the sewing may be performed in either direction of the length of the shoe and that 65 under proper conditions the sewing opera-

tion may be performed without removing the last from the shoe. Fig. 5 shows diagrammatically mechanism for performing the operation of sewing the upper to the innersole of the shoe with the last removed by 70 means of a straight needle sewing machine, N indicating the needle and S the support for the sole. This operation may be performed by any suitable sewing machine.

Supposing the last to have been removed 75 during the sewing operation, it is again placed in the shoe and the shoe is completed by the attachment of an outsole and heel which may, as shown, be a spring heel. Preferably also a welt is laid over the outwardly extending margin of the upper and is secured by the stitches which also hold the outsole. A shoe thus completed is shown in Fig. 6.

Having thus described my invention, what 85 I claim as new and desire to secure by Letters Patent of the United States is:

1. That improvement in methods of making shoes which consists in assembling upon a last an upper and an innersole having its 90 margin projecting beyond the bottom of the last, staple lasting the toe and heel portions of the upper to the innersole, removing the last, stitching the shoe upper to the sole along the sides of the shoe, reinserting 95 the last, and completing the shoe in the usual manner.

2. That improvement in the art of making stitchdown shoes which consists in attaching an outturned upper to an innersole 100 by staples and stitches in alternately arranged sections, and then attaching an outsole to the upper and innersole by stitches only.

3. That improvement in the art of making stitchdown shoes which consists in attaching an outturned upper to an innersole by stitches at the sides of the shoe and by staples at the ends of the shoe, and then attaching an outsole to the upper and innersole by 105 stitches extending about the periphery of the shoe.

4. That improvement in the art of making stitchdown shoes which consists in lasting and attaching an outturned upper to the 115 sole about the toe and heel portions of the shoe while the shoe is on the last, removing the last, and sewing the portions of upper between the lasted portions to the innersole.

5. That improvement in methods of making shoes which consists in assembling upon a last an unmolded upper and an innersole having its margin projecting beyond the bottom of the last, staple lasting the toe portion of the upper to the innersole, removing 120 the last, securing the shoe upper to the sole along the sides of the shoe by non-metallic means, reinserting the last, and completing the shoe in the usual manner.

6. That improvement in the art of mak-

180

ing stitchdown shoes which consists in attaching an outturned upper to a sole by staples and stitches in alternately arranged sections about the periphery of the shoe, the toe section being stapled, then applying a welt to cover the staples and stitches and sewing the welt to the upper and sole.

7. That improvement in the art of making stitchdown shoes which consists in attaching an outturned upper to a sole by 10 stitches at the sides of the shoe and only by staples at an end of the shoe, then applying a welt over the staples and stitches and attaching the welt, upper and sole together by 15 a continuous line of stitches.

8. That improvement in the art of making stitchdown shoes which consists in lasting and attaching an outturned upper to the sole about the toe of the shoe while the shoe 20 is on the last, then removing the last and sewing the upper to the innersole at the sides only of the shoe.

9. That improvement in the art of making stitchdown shoes which consists in attaching sections of an outturned upper to the innersole by staples only, and in attaching other sections of the upper to the in- 25

nersole by stitches only, the sewed sections being at the sides of the shoe.

10. That improvement in the art of making 30 stitchdown shoes which consists in attaching an outturned upper to the sole by lasting and stapling it about the toe and at single points on opposite sides of the ball in the angle between the side of the last and the 35 projecting margin of the sole, securing the upper to the sole by stitches from the lasted portion at the tip line to the heel breast line, then applying a welt over the staples and 40 stitches and connecting the welt, upper and sole together by a continuous line of uniform fastenings.

11. That improvement in the art of making 45 stitchdown shoes which consists in lasting and stapling an outturned upper to the sole about the toe, sewing the outturned upper to the sole at the sides of the shoe, then applying a welt to cover the staples and 50 stitches and sewing the welt to the upper and sole.

In testimony whereof I have signed my name to this specification.

ERNEST C. BEAUMONT.
